BUNGHOLE STOPPER

Victor Alvear, Passaic, N. J.

Application April 25, 1940, Serial No. 331,541

12 Claims. (Cl. 217—110)

The invention relates to bunghole stoppers, and more particularly to a stopper of the type in which a draw rod or tube may be inserted within a keg, barrel or other container without removing the stopper from said container.

At the present time, it is a common practice to close the bunghole of a keg or barrel containing liquor under pressure, with a compressible wooden stopper having a liquid and gas tight joint with a metal bushing or liner imbedded in the material of the keg or barrel having a central bunghole extending therethrough.

Not only are the stoppers commonly used expensive, but when tapping a keg or barrel, it is necessary to remove the stopper before inserting the draw rod or tube, and quite frequently such stoppers are forced inwardly of the barrel or keg, thus making it necessary to remove same from the keg or barrel after it has been emptied and when cleaning it prior to the subsequent re-filling thereof with the liquor. This also is a troublesome operation.

With the above conditions in mind, I have provided a bunghole stopper embodying therein a metal shell which is so formed that when it is inserted in the metal bushing or liner, it will be automatically locked in position therein in a manner to resist displacement from pressure within the keg or barrel and yet permit the withdrawal of the stopper from the bushing or liner when the keg or barrel has been emptied and it is desired to thoroughly wash and clean same preparatory to future use.

The metal shell is provided with an envelope of compressible material as to the portion thereof entering the bushing or liner, and extending across the bottom of the shell in a manner to close an opening through said bottom for the insertion of a draw rod or tube into the keg or barrel.

The compressible material is of a thickness to form a liquid and gas tight joint between the skirt of the metal shell and the wall of the bushing or liner, and has sufficient tenacity to resist such distortion as will result in the formation of voids permitting the escape of gas from the keg or barrel, while being readily rupturable by a draw rod or tube when the same is inserted through the open bottom of the shell and the portion of the envelope exposed through said open bottom. This material is provided with an exterior coating which will resist deterioration as a result of contact of the contents of a keg or barrel therewith, and will also assist in the formation of a gas and liquid tight joint between

the metal shell and the wall of the bushing or liner. The envelope is also preferably so secured to the skirt of the metal shell as to prevent any possibility of the separation of these parts, and 5 also to resist any such tendency toward slippage of the envelope in relation to the shell as might result in rupturing of the envelope when applying the stopper to the bunghole bushing or liner.

Preferably, the inside of the envelope is provided with a surface preventing deterioration of 10 the material of the envelope from exposure to atmospheric conditions, and also to seal any voids in the material of the envelope and of the outer coating thereof in a manner to prevent the escape of gas through the stopper.

The bottom of the metal shell is so formed as to impart to the shell, at this point, sufficient rigidity to prevent deformation of this portion of the stopper when forcing it within the opening of 20 a bushing or liner, due to resistance to the movement of the stopper, and at the same time avoid possible distortion of the bottom of the stopper when pressure is applied thereto about the exposed portion of the envelope when applying it to the keg or barrel.

The invention consists in a bunghole stopper embodying therein a skirted metal shell having an open top, outwardly projecting means about 30 said top adapted to bite into the wall of a bunghole, and an opening through the bottom thereof for the passage of a draw rod, and a cupped envelope of compressible material inclosing the skirt of said shell to a point slightly below the top thereof and extending across the open bottom thereof, the material of said envelope being of a thickness to extend beyond said outwardly 35 projecting means at the top of said shell and having an exterior protective coating resistant to the contents of a keg or barrel whereby a seal 40 is provided between the skirt of said shell and the wall of the bunghole, and in such other novel features of construction and arrangement of parts as are hereinafter set forth and described, and more particularly pointed out in the claims 45 hereto appended.

Referring to the drawing,

Fig. 1 is a sectional view of a fragmentary portion of a container adjacent the bunghole, showing a stopper embodying the invention applied thereto;

Fig. 2 is a plan view of the metal shell forming a part of the stopper;

Fig. 3 is a section on the line 3—3 of Fig. 2;

Fig. 4 is a sectional view through the cupped envelope; and

Fig. 5 is a sectional view of a fragmentary portion of the stopper upon a greatly enlarged scale.

Like numerals refer to like parts throughout the several views.

In the accompanying drawing, a portion of a container, adjacent the bunghole, is shown at 10. This container has an opening therethrough provided with a metallic bushing or liner 11 of well known construction, having a bunghole opening 12 therethrough. The opening 12, is in actual practice, about three-quarters of an inch in diameter.

A stopper embodying the invention is adapted to be inserted in this opening 12 before the container has been filled with liquor, and to be removed therefrom after the liquor has been drawn from the container and it is necessary to thoroughly cleanse same before re-filling.

While the stopper is in place in the bunghole of a filled container, the portion thereof exposed within the container is subjected to the action of vapors, and splashing liquor during transportation, and there is a constant tendency of the gas pressure within the container to force the stopper out of the bunghole.

Owing to these conditions, it is essential that the stopper be firmly locked to the wall of the opening 12, so as to prevent possible displacement thereof by gas pressure within the container; that a portion of the stopper be firmly compressed and engaged with the wall of the opening to form a liquid and gas tight joint about the stopper, and that the surface of the stopper exposed to the contents of the container be of a nature to resist deterioration as a result of exposure to gas, vapors and liquids within the container.

The stopper of the invention, as shown in the accompanying drawing, embodies therein a metal shell having a skirted portion 13 of slightly smaller diameter than the opening 12. This shell has an open top and an opening 14 through the bottom thereof extending to adjacent the skirt 13. Adjacent the open top of the shell, is outwardly projecting means consisting of a flared edge or flange 15, having a raw or roughened edge which will readily bite into and interlock with the material of the bushing or liner 11.

The skirt 13 of the shell has a slight downward and inward taper, and the flange 15 projects from the largest diameter of this shell to an extent of only a few thousandths of an inch. The width of the flange is capable of variation in accordance with the thickness of the sealing material of the envelope. In actual practice, the taper from top to bottom of the skirt of the shell is about .004 of an inch.

In such stoppers as have been actually used, the flange 15 extends beyond the outside diameter of the shell to an extent of approximately .01 of an inch.

As will appear hereinafter, the thickness of the compressible material of the envelope relied upon for securing an effective sealing against the escape of gases, liquids and vapors, is approximately .002 of an inch greater than the greatest diameter of the flange 15, and the envelope is so formed and secured in relation to the metal shell as to permit the material thereof to be compressed to a diameter slightly less than the greatest diameter of the flange.

The various dimensions given above are not critical, but illustrate those conditions which have been found to give highly satisfactory re-

sults and to meet the conditions of slight variation in the diameters of different bunghole openings 12.

The metal shell serves as a support for the envelope of packing material; to secure the stopper in its entirety against displacement after being forced into the bunghole opening, and as a means for inserting and removing a stopper from said opening.

The sealing envelope consists of a cupped member 16 of compressible fibrous material such as sheet paper. The side wall of this envelope closely embraces the skirt 13 of the metal shell and extends to a point spaced slightly below the outwardly flared or flanged portion 15 of this shell, thus providing space for the flow of the fibrous material as the stopper is being driven into the bunghole opening. The depth of the skirt 13, in actual practice, is about a quarter of an inch, while the height of the wall 17 of the cupped envelope is approximately three-sixteenths of an inch.

To prevent deterioration of the sheet paper which forms the core of the cupped envelope 16, either by absorption of liquid within the container, or by the action of vapors and gases thereon, I provide this envelope with an outer protective facing or film 18 which is repellent to such substances. In actual practice, I have found that a thin coating of chlorinated rubber is highly satisfactory for this purpose, particularly as this material has no tendency to strip from the core as a result of the drag incidental to driving the stopper within the bunghole opening. The outside taper of the cupped envelope also is a factor in preventing disruption of the material therein.

The other face of the material of the cupped envelope is preferably provided with a lining 19 of a metal foil such as aluminum, firmly bonded to this surface of the material of the envelope. This lining supplements the protective facing or film 18 in preventing the escape of gas from the container in the event of minute voids in the core and in said protective facing. This lining 19 extends across and is exposed through the bottom opening 14 of the metal shell, and serves to protect the material of the envelope from atmospheric and other conditions to which this exposed surface is exposed.

When assembling a stopper, a heat fusible adhesive layer or stratum 20, between the liner 19 and the skirt 13 of the metal shell, is employed. By bonding the side wall 17 of the envelope to the outside of the skirt 13 of the metal shell, movement of the envelope in relation to the skirt is prevented, when applying the stopper to, or removing it from, the bunghole. This is desirable as it prevents tearing of the material of the envelope at the juncture of the side wall and the bottom of the cupped envelope when applying the stopper to the container.

The non-absorbent facing 18 prevents adherence of the material of the envelope to the inner wall of the bushing or liner 11, and any moisture upon this surface will tend to reduce the drag upon the envelope when applying the stopper to a container.

While the slight taper of the stopper below the flange 15 and the slight rounding of the cupped envelope at the juncture of the side wall and the bottom thereof, will reduce the tearing strains upon the material of the envelope at this point, this taper will also permit the stopper to adapt itself to different bunghole bushings in which

there is a slight variance in the diameters of the openings therethrough for the stopper.

Thin tin plate is used for forming the metal shell, and in applying the stopper to a container, force is applied to the shell at the top of the flare or flange 15, and also to the bottom of the shell about the opening 14 therethrough. The flange 15 stiffens the shell adjacent the top thereof. Adjacent the bottom of the shell, however, the tendency of the skirt to collapse is very much greater than about the top of the shell.

To stiffen the skirt about the bottom thereof, I have found it highly desirable to not only provide an inwardly directed flange about the opening 14, but to give this flange the form of a bead 21, which so stiffens the bottom of the shell as to not only prevent any possible collapsing of the skirt 13, but to permit the application of the desired force adjacent the bottom of the shell when applying the stopper to a bunghole without placing undue stresses upon the bottom of the cupped envelope.

In applying stoppers embodying the invention to, and removing them from, a container, special tools are required. Such tools, however, form no part of the present invention, and are therefore not shown nor described in detail.

In applying a stopper to a container, the lower portion thereof is inserted in the bunghole 12, the side wall of the cupped envelope 16 having a close fit with the wall of the bunghole opening. The stopper is driven within said opening by means of a hammer or mallet and the special inserting tool above referred to which is engaged with the beaded inwardly directed bottom flange 21 and the outwardly flared top flange 15.

As the stopper is forced inwardly, the material of the cupped envelope is gradually compressed, the extent of compression being controlled by the diameter of the bunghole opening 12 and the outside taper of the stopper. Such diameters may vary approximately a thousandth of an inch, but the taper of the stopper and the compressibility of the material of the envelope 16 ensures a liquid and gas tight joint completely about the stopper at some point.

The material of the envelope is subjected to a drag because of its frictional engagement with the wall of the opening 12, and I have found it desirable to permit slight flow of this material in order to overcome any tendency of the drag to tear the material and thus form channels through which gas or liquid might escape from the container. By spacing the top of the side wall slightly below the outwardly directed flare or top flange 15, ample space is provided for the flow of the material of the envelope upwardly to an extent to prevent its mutilation, while at the same time an effective sealing joint between the stopper and the bushing or liner of the bunghole is secured.

The cylindrical skirt of the shell and the reinforcing flanges at the top and bottom thereof prevent any such collapsing of the shell as might interfere with the formation of a tight seal.

When a stopper is once in place in the bunghole, it is merely necessary to force the draw rod or tube through the thin material of the cupped envelope exposed through the bottom opening 14 of the metal shell, and secure it in place in the usual manner. This rod will readily rupture the material at this point, but will not disturb the seal between the side wall of the envelope and

the wall of the opening 12 of the bushing or liner 11.

When it is desired to remove the stopper from the bushing or liner, another tool is passed through the open bottom of the shell and engaged with the lower face of the envelope below the beaded flange 21, and an upward pull applied to the stopper.

In driving the stopper within the opening 12, the outwardly flared top flange 15 will be forced into engagement with the material of the wall of the opening 12, and the edge of this flange will take a firm bite upon the material of the bushing. Hence, outward stresses from gas pressure within

the container will merely serve to strengthen the locking action between this flange and said wall. Resistance to such pressure by the flange serves to flatten it slightly and increases the locking action.

When inserting the stopper in the opening 12, the outside diameter of the cylindrical portion of the envelope will be slightly greater adjacent the flange 15 than the greatest diameter of this flange, but the diameter of the cylindrical portion adjacent the bottom of the stopper is slightly smaller than the diameter of said flange 15. The force applied to the stopper will compress the material of the envelope to an extent to reduce its diameter to that of the opening 12, thus forming an effective seal.

The depth of the bite of the flange 15 into the material of the bushing 11 may be a mere fraction of a thousandth of an inch, but has been found adequate to prevent the blowing out of the stopper by gas pressure within the container. While, in packaging beer, this pressure is ordinarily approximately fifty pounds to the square inch, the surface of the stopper exposed to this pressure is only approximately one-half of a square inch.

The outer facing 13 must be of a material which will be acid and liquid resistant and which will impart no taint or characteristic flavor to the contents of a container, although this latter is of secondary importance since a considerable bulk of beer or other liquor is packaged in the containers and the area of the envelope exposed to such contents is small.

It is not my intention to limit the invention to the precise details of construction herein stated. The dimensions given may be varied, and this variance may be considerable with stoppers of greater diameters than that herein referred to, or which are for use with bushings or liners 11 differing from that shown in the drawing.

While I have referred to the use of a heat fusible adhesive in securing the envelope to the skirt of the metal shell, this is a manufacturing detail and, if desired, a fusible adhesive which sets when cold, or an adhesive which sets under heat and pressure may be employed. Many such adhesives are well known in the bottle closure industry.

Having described the invention, what I claim as new and desire to have protected by Letters Patent is:

1. A bunghole stopper embodying therein a skirted metal shell having an open top, outwardly projecting means about said top adapted to bite into the wall of a bunghole, and an opening through the bottom thereof for the passage of a draw rod, and a cupped envelope of compressible material inclosing the skirt of said shell to a point slightly below the top thereof and extending across the open bottom thereof, the ma-

terial of said envelope being of a thickness to extend beyond said outwardly projecting means at the top of said shell, and having an exterior protective coating resistant to the contents of a keg or barrel whereby a seal is provided between the skirt of said shell and the wall of the bunghole.

2. A bunghole stopper embodying therein a skirted metal shell having an open top, an outwardly and upwardly flared flange about said top adapted to bite into the wall of a bunghole, and an opening through the bottom thereof for the passage of a draw rod, and a cupped envelope of compressible material inclosing the skirt of said shell to a point slightly below the top thereof and extending across the open bottom thereof, the material of said envelope being of a thickness to extend beyond said outwardly projecting flange at the top of said shell, and having an exterior protective coating resistant to the contents of a keg or barrel whereby a seal is provided between the skirt of said shell and the wall of the bunghole. 10 15 20

3. A bunghole stopper embodying therein a skirted metal shell having an open top, an outwardly and upwardly flared flange about said top adapted to bite into the wall of a bunghole, an opening through the bottom thereof for the passage of a draw rod, and an inwardly directed reinforcing flange about said opening, and a cupped envelope of compressible material inclosing the skirt of said shell to a point slightly below the top thereof and extending across the open bottom thereof, the material of said envelope being of a thickness to extend beyond said outwardly projecting flange at the top of said shell, and having an exterior protective coating resistant to the contents of a keg or barrel whereby a seal is provided between the skirt of said shell and the wall of the bunghole.

4. A bunghole stopper embodying therein a skirted metal shell having an open top, an outwardly and upwardly flared flange about said top adapted to bite into the wall of a bunghole, an opening through the bottom thereof for the passage of a draw rod, and an inwardly directed reinforcing beaded flange about said opening, and a cupped envelope of compressible material inclosing the skirt of said shell to a point slightly below the top thereof and extending across the open bottom thereof, the material of said envelope being of a thickness to extend beyond said outwardly projecting flange at the top of said shell, and having an exterior protective coating resistant to the contents of a keg or barrel whereby a seal is provided between the skirt of said shell and the wall of the bunghole.

5. A bunghole stopper embodying therein a skirted metal shell having an open top, outwardly projecting means about said top adapted to bite into the wall of a bunghole, and an opening through the bottom thereof for the passage of a draw rod, the skirt of said shell being tapered from adjacent the top toward the bottom thereof, and a cupped envelope of compressible material inclosing the skirt of said shell to a point slightly below the top thereof and extending across the open bottom thereof, the material of said envelope being of a thickness to extend beyond said outwardly projecting flange at the top of said shell, and having an exterior protective coating resistant to the contents of a keg or barrel whereby a seal is provided between the skirt of said shell and the wall of the bunghole.

6. A bunghole stopper embodying therein a

skirted metal shell having an open top, outwardly projecting means about said top adapted to bite into the wall of a bunghole, and an opening through the bottom thereof for the passage of a draw rod, and a cupped envelope of compressible fibrous material inclosing the skirt of said shell to a point slightly below the top thereof and extending across the open bottom thereof, the material of said envelope being of a thickness to extend beyond said outwardly projecting means at the top of said shell, and having an exterior protective coating resistant to the contents of a keg or barrel whereby a seal is provided between the skirt of said shell and the wall of the bunghole.

15 7. A bunghole stopper embodying therein a
skirted metal shell having an open top, outward-
ly projecting means about said top adapted to
bite into the wall of a bunghole, and an opening
20 through the bottom thereof for the passage of a
draw rod, and a cupped envelope of compressible
fibrous material inclosing the skirt of said shell
to a point slightly below the top thereof and ex-
tending across the open bottom thereof, the ma-
terial of said envelope being of a thickness to ex-
25 tend beyond said outwardly projecting means at
the top of said shell, and having an exterior pro-
tective coating of chlorinated rubber whereby a
seal is provided between the skirt of said shell
and the wall of the bunghole.

30 8. A bunghole stopper embodying therein a
skirted metal shell having an open top, outward-
ly projecting means about said top adapted to
bite into the wall of a bunghole, and an opening
through the bottom thereof for the passage of a
35 draw rod, and a cupped envelope of compressible
material inclosing the skirt of said shell to a point
slightly below the top thereof and extending
across the open bottom thereof, the material of
said envelope being of a thickness to extend be-
yond said outwardly projecting means at the top
40 of said shell, and having an exterior protective
coating resistant to the contents of a keg or bar-
rel whereby a seal is provided between the skirt
of said shell and the wall of the bunghole, and an
interior lining whereby the escape of gas through
45 the material of said envelope is prevented.

1. The material of said envelope is prevented.

9. A bunghole stopper embodying therein a skirted metal shell having an open top, outwardly projecting means about said top adapted to bite into the wall of a bunghole, and an opening through the bottom thereof for the passage of a draw rod, and a cupped envelope of compressible material inclosing the skirt of said shell to a point slightly below the top thereof and extending across the open bottom thereof, the material of said envelope being of a thickness to extend beyond said outwardly projecting means at the top of said shell, and having an exterior protective coating resistant to the contents of a keg or barrel whereby a seal is provided between the skirt of said shell and the wall of the bunghole, and an interior metal foil lining bonded thereto whereby the escape of gas through the material of said envelope is prevented.

1 65 10. A bunghole stopper embodying therein a
skirted metal shell having an open top, outwardly
projecting means about said top adapted to bite
into the wall of a bunghole, and an opening
through the bottom thereof for the passage of a
1 70 draw rod, and a cupped envelope of compressible
fibrous material inclosing the skirt of said shell
to a point slightly below the top thereof and ex-
tending across the open bottom thereof, the ma-
terial of said envelope being of a thickness to ex-
1 75 tend beyond said outwardly projecting means at

the top of said shell, and bottom thereof, the material of said envelope being of a thickness to extend beyond said outwardly projecting means at the top of said shell, and having an exterior protective coating of chlorinated rubber whereby a seal is provided between the skirt of said shell and the wall of the bunghole, and an interior metal foil lining bonded thereto whereby the escape of gas through the material of said envelope is prevented.

11. A bunghole stopper embodying therein a skirted metal shell having an open top, outwardly projecting means about said top adapted to bite into the wall of a bunghole, and an opening through the bottom thereof for the passage of a draw rod, a cupped envelope of compressible material inclosing the skirt of said shell to a point slightly below the top thereof and extending across the open bottom thereof, the material of said envelope being of a thickness to extend beyond said outwardly projecting means at the top of said shell, and having an exterior protective coating resistant to the contents of a keg or barrel whereby a seal is provided between the skirt of said shell and the wall of the bunghole, and an interior metal foil lining bonded thereto whereby

the escape of gas through the material of said envelope is prevented, and means for bonding said envelope to the skirt of said metal shell.

12. A bunghole stopper embodying therein a skirted metal shell having an open top, an outwardly and upwardly flared flange about said top adapted to bite into the wall of a bunghole, and an opening through the bottom thereof for the passage of a draw rod, the skirt of said shell being tapered from adjacent the top toward the bottom thereof, a cupped envelope of compressible fibrous material of a thickness to extend beyond the edge of said flange, and inclosing the skirt of said shell and extending across the open bottom thereof whereby a seal is provided between the skirt of said shell and the wall of the bunghole, the top of the side of said cup being spaced from said outwardly and upwardly flared flange, said fibrous material having an exterior protective coating of chlorinated rubber, and an interior metal foil lining bonded thereto whereby the escape of gas through said fibrous material is prevented, and means for bonding the side of said cupped envelope to the skirt of said metal shell.

VICTOR ALVEAR.
